DISPLAY CABINET

Frank W. Edwards, Cleveland, Ohio, assignor to
 The Telling Belle Vernon Company, Cleveland,
 Ohio, a corporation of Ohio

Application June 26, 1941, Serial No. 399,842

1 Claim. (CL. 88—74)

This invention relates to a combined storage and display cabinet and more particularly to the refrigerator type of cabinet especially adapted for the storage of ice cream and other dairy products, which are dispensed therefrom from time to time according to customer demands.

Such storage cabinets for dairy products and particularly ice cream are usually provided with deep recesses or wells, to receive one or more cans of bulk ice cream. Interposed between the external walls of the cabinet and the walls of the recesses is a set of cooling coils of a refrigerator unit. A closure is necessary, of course, to protect the products from the air at room temperature and heretofore such closures have been a source of great inconvenience and annoyance. In the past these closures comprised individually hinged or removable lids, one above each recess or container. The cabinets used in the past, therefore, generally were provided with a half dozen or more lids, below any one of which might lie the particular flavor of ice cream desired, and it is a usual sight to see clerks make three or four wrong guesses before finding the desired flavor.

Another, and perhaps more serious disadvantage of closures of this sort is the concealment of the product from the view of the prospective customer. He must be beguiled into purchasing by the display of mere advertising matter and must form his decision of choice from printed lists of flavors. In other words, the element of eye-appeal of the deliciously tempting product itself is lacking.

The present invention has for its general object, therefore, the provision of a closure for a refrigerator cabinet which will be convenient in use and lacking in the sources of annoyance of the types used in the past, and which will allow the product itself to be seen with ease, not only by the clerk, but by the customer also, and will call the attention of the customer to itself in a most satisfactory manner.

A further object is the provision of such a closure in a form of simple design and adapted to be constructed of simple materials and, hence, to be economical in manufacture.

Other objects and advantages of this invention will become more apparent from the following description, reference being had to the accompanying drawings in which there is illustrated a preferred embodiment of the invention. The novel and essential characteristics of the invention will be summarized in the claim.

In the drawings, Fig. 1 is a transverse section 55

of a combined storage and display cabinet constructed in accord with the present invention, the plane of the section being represented by the lines 1—1 on Fig. 2; Fig. 2 is a front elevation of the cabinet and closure of Fig. 1; Fig. 3 is an end elevation of the cabinet; and Fig. 4 is a rear elevation of the cabinet.

Referring now to the drawings, the cabinet of the present invention comprises a base 10 which is surmounted by a removable closure member 20. A plurality of recesses or wells 11, each of which may accommodate a plurality of containers or cans 12 of ice cream, are arranged side by side in the cabinet. The cabinet may also be provided with an additional well 13 for the storage of packaged ice cream, ice cream cakes, and other dairy products 14.

The wells 11 and 13 may be cooled by any suitable refrigeration system. As illustrated in the drawings, the wells are surrounded by cooling coils 15 leading from a refrigerating unit 16, which may be of the usual type and conveniently housed within the cabinet base 10. A heat insulating material 10a is interposed between the cooling coils and the external walls of the base. As will be seen in Fig. 1, the depth of the wells is greater than that of the cans, thereby providing air spaces 17 within the wells above the upper level of the cans. The well walls in the regions above the cans may conveniently flare outwardly, as shown at 11a, to facilitate access to the contents of the cans. The top of the cabinet comprises a plane surface 18, broken only by the well openings and meets the end and side walls of the cabinet at substantially right angles, thus providing a flat, horizontal rim 19 completely about the periphery of the base. Upon this rim is seated the closure member 20 which will now be described.

The object of a storage cabinet of this kind is, of course, to keep the contents cooled to the desired temperature and, therefore, some sort of insulation from the heat of the surrounding air should be provided. I have discovered that a quiescent layer of air of moderate depth will provide sufficient protection in a manner fully as efficient as that of a heavily insulated lid. In addition, the air possesses the highly advantageous quality of transparency.

The closure member, as best illustrated in Fig. 1, has been so arranged as to provide the insulating blanket of air, above mentioned, as well as to protect such blanket from air currents so as to maintain its quiescent condition and at the same time provide easy access for dispensing the

protected contents, and to enable the contents to be viewed from the exterior of the cabinet by the customer and clerk without necessitating the removal of the cover. The closure member 20 is of inverted V shape in cross section, the slanting front and rear walls 21 and 22 respectively, and the end walls 23 being joined at the top by a narrow horizontal roof portion 24 and terminating at their lower edges in an uninterrupted, horizontal, peripheral flange portion 25. This flange portion rests upon the cabinet rim 19 heretofore described. A sealing gasket 26 of soft rubber or the like is preferably interposed between the flange of the closure 20 and the rim 19 of the base. A depending lip or skirt 27 may be provided at the outer edges of the flange 25, which lip may snugly embrace the upper region of the base and thus serve as a positioning means for the closure member 20, and at the same time provide a sanitary and easily cleaned structure. Such a construction permits the closure member 20 to be easily and conveniently removed and replaced when it becomes necessary to change bases should the cooling unit become defective and facilitate the use of the closure on existing bases.

Access to the interior of the closure 20, and, hence, to the contents of the cabinet is provided by a pair of sliding doors 30, Figs. 1 and 4, covering an opening in the rear wall 22 of the closure. These doors preferably comprise sheets of glass, the edges of which are covered by narrow metal frames 31 which slide in grooved guideways 32 carried by the rear wall. Two such guideways are provided whereby the doors may be telescoped to one side or the other as desired. Inconvenience is eliminated as the inward slant of the rear walls of the closure 20 allows the clerk to project his arm into the cabinet in a normal manner to remove the contents thereof.

The insulating blanket of air heretofore referred to, is that layer of air which is disposed between a horizontal plane passing through the lower extremity of the door opening and the upper face of the cabinet base. This blanket of air is confined and retained in a quiescent state by reason of the fact that the walls of the closure are imperforate except for the door opening which is normally closed by doors 30 and 31. Hence, the air lying below the level of the broken line 33 in Fig. 1 is normally in a quiescent condition, disturbed only by slight drafts which might possibly ruffle its upper boundary when the door is temporarily open and by the hand of the clerk in penetrating it to reach the contents of the wells. Such disturbances are temporary and minor as the air comes again to rest practically immediately upon their cessation. The use of sliding doors, as heretofore described, is an additional factor in the preservation of the quiescent state of this blanket of air as no turbulence is caused by their manipulation.

Since the blanket of air is chilled to a much lower temperature than the surrounding atmosphere it lies heavily upon the cabinet surfaces and the contents and as air is a very efficient heat insulator, the contents are quite easily kept at the desired temperature. In fact, it has been found in actual use that the refrigerator unit is

called into operation much less frequently than it is when old style closure arrangements are used.

The present invention also promotes increased sales of the stored product since the arrangement is such that the product is visible to the customer at all times. The inverted V-shape of the closure element 20 aids materially in accomplishing this result. As shown in the drawings, the slanting glass doors 30 are provided with a silvering 5 coat so as to constitute inwardly facing mirrors and a glass window 40 is set into the slanting front wall 21. Light rays 41 from the cabinet contents are thus reflected by the mirrored doors and directed forwardly, as at 42, through the window 40 to the eyes of a person who may be in any 10 part of the store or restaurant, for example, which is forwardly of the cabinet. In effect, the containers are raised and tipped to the broken line position 12a in Fig. 1 so that the customer looks directly into the containers and can view 15 their contents in a manner illustrated by Fig. 2. Upon closer approval, the customer may look down through the window 40 to see the contents directly, as indicated by the light rays 43 in Fig. 1. 20 If desired, the closure member 20 may be provided with a source of illumination such as electric lamps elements generally indicated at 56 in Fig. 1 as being positioned immediately below the narrow 25 upper wall of the closure member, the V-shaped walls of which conveniently provide reflector surfaces.

It will be seen that the device of this invention may be economically manufactured of light sheet metal with the simple glass window and doors 30 mounted therein in a quite simple manner. While a preferred embodiment of the invention has been illustrated, I am aware that numerous variations and adaptations may be made within the spirit and scope of my invention.

I claim:

In a display cabinet, a substantially enclosed container having a horizontal top provided with article receiving recesses, a cover for said container and comprising a metal plate formation of an inverted V shaped cross section having a horizontal outward extending flange extending around its bottom edge to rest on the top wall of said container, said flange being provided with a downward projecting lip to embrace the side walls of said container to thereby position said cover, each of the sloping sides being provided with enlarged openings spaced a substantial distance from the top and bottom of said cover to thereby maintain substantially quiescent blankets of air above and below said openings, internally mirrored doors slidably mounted on said cover and within the confines thereof and arranged and adapted to close one of the openings, and a transparent member permanently closing the other opening, means in said cover adjacent the vertex of said V and within the upper quiescent blanket of air to directly illuminate the contents of the container, said means being positioned to avoid direct illumination of said mirrored walls, whereby the illuminated contents of said container are visible from the exterior of said cover either directly through said transparent closure or by reflection of said mirrored doors.

FRANK W. EDWARDS.
